CLAIM

The ornamental design for a slow-consume animal feeding coupling round insert, as shown and described.

DESCRIPTION

FIG. 1 is a perspective view of an animal feeding coupling round insert in accordance with the present invention; FIG. 2 is a top view of the animal feeding coupling round insert of FIG. 1; FIG. 3 is a front-side view of the animal feeding coupling round insert of FIG. 1; FIG. 4 is a rear-side view of the animal feeding coupling round insert of FIG. 1; FIG. 5 is a right-side view of the animal feeding coupling round insert of FIG. 1; FIG. 6 is a left-side view of the animal feeding coupling round insert of FIG. 1; FIG. 7 is a bottom view of the animal feeding coupling round insert of FIG. 1; and, FIG. 8 is a perspective exploded view of the animal feeding coupling round insert of FIG. 1 to fit in a feeding bowl shown in broken lines. The broken lines shown in the Figures are for environmental purposes only and form no part of the claimed design.
